Primary Examiner — Antoine Duval Davis(74) *Attorney, Agent, or Firm* — Kilpatrick Townsend & Stockton LLP(57) **CLAIM**

The ornamental design for a bumpboard, as shown and described.

DESCRIPTION

FIG. 1 is a perspective view of a bumpboard showing my new design;

FIG. 2 is a bottom plan view thereof;

FIG. 3 is a top plan view thereof;

FIG. 4 is a right side elevational view thereof;

FIG. 5 is a left side elevational view thereof;

FIG. 6 is a front elevational view thereof; and,

FIG. 7 is a rear elevational view thereof.

The broken line showing is for illustrative purposes only and forms no part of the claimed design.
